RECOILLESS GUN MECHANISM

Carolus L. Eksergian, Detroit, Mich., assignor, by
mesne assignments, to United States of Amer-
ica

Application April 5, 1944, Serial No. 529,576

4 Claims.

(Cl. 89—1)

1

This invention relates to guns, cannons and the like, more particularly to those of the recoilless type wherein a plurality of vanes are disposed in a gas discharge passage for counteracting the tendency toward rotation of the gun incident to rifling of the gun barrel.

The primary object of the present invention is the provision in a gas discharge chamber of a recoilless gun or the like of an improved vane arrangement of simplified construction and means for mounting the same which is capable of economical manufacture and easy assembly.

With the above and other objects in view which will be apparent from the following description to those skilled in the art to which the invention appertains, the present invention consists of certain features of construction and combinations of parts to be hereinafter described with reference to the accompanying drawing, and then claimed.

In the drawing which illustrates a suitable embodiment of the invention:

Figure 1 is an end view of the recoilless gun mechanism, and

Figure 2 is a longitudinal section taken approximately on line 2—2 of Figure 1.

Referring to the drawing, the recoilless mechanism includes an elongated casing 5 coaxial with and externally threaded to the rearward end of a gun barrel 6, the internal wall of the casing 5 being contoured to provide a chamber 7 and an axially opening Venturi passage 8 having a restricted throat 9.

Arranged within the chamber 7 is a spider element 10 having a hub 11 and radially outwardly extending legs 12. The ends of the legs 12 are engaged with that portion of the inner wall surface of the casing which tapers inwardly toward the throat 9.

The spider element 10 is formed with an axial opening 13 which supports a tubular element 14, the tubular element having a shouldered or flange portion 15 which seats in a counterbore or recess 16 at the forward side of the hub 11 to prevent movement of the tubular element 14 rearwardly through the opening 13. The tubular element 14 is closed at its forward end by a screw 17 having a rounded head, and at its rearward end by a cap screw 18 having a chamber 19 therein and a pair of small apertures 20 through its head. Forwardly of the spider element 10, the passageway 21 which extends from end to end of the tubular element 14 is provided with cross passages 22.

This forward portion of the tubular element, that is, the portion which extends forwardly of

the spider element 10, supports the explosive charge 23, the pressure developed from the firing of the same projecting the shell or projectile (not shown) from the gun barrel 6. The charge 23 is of annular formation and is inserted through the muzzle end of the gun barrel and slid over the tubular element 14, the rounded head of the screw 17 facilitating the disposition of the charge 23 on the tubular element 14.

10 A flash charge (not shown) is carried in the chamber 19 of the screw 18 and is electrically ignited by ignition wires (not shown) extending through the apertures 20. The flash or flame resulting from ignition of the flash charge travels through the passageway 21 and thence through cross passages 22 to ignite the propelling charge 23.

15 In order to counteract and resist the rotative effect of the gun barrel, incident to the rifling of the gun barrel, during firing of the projectile, a vaned member 24 is utilized. The vaned member 24 embodies a conical hub 25 and a plurality of vanes 26 extending outwardly therefrom, the plane of each vane being at an angle to the axis 20 of the hub 25 whereby the gases exhausting through the Venturi passage 8 will impinge against the side faces thereof. The vanes are of a gradually increasing depth in the rearward direction and have substantially the same taper as 25 the exhaust side of the Venturi passage 8. The hub 25 is provided with a central opening 27 through which the rearward side of the tubular element 14 extends, and the end of this portion of the tubular element 14 is externally threaded 30 to carry a nut 28. Upon tightening of the nut 28 against the hub 25 of the vaned member 24, the vaned member 24 and the spider element 10, by reason of the engagement of the shoulder 15 therewith, are moved relatively toward each 35 other, thus bringing the ends of the legs 12 into abutting engagement with the wall surface of the chamber 7 and the outermost tapered end faces of the vanes 26 into engagement with the tapered wall of the discharge side of the Venturi 40 passage 8. Tightening of the nut 28 thus produces a clamping effect which securely locks the spider element 10 and vaned member 24 in position without the necessity of utilizing supplemental securing means, such as for example, bolts 45 and screws.

45 There is thus provided a novel arrangement whereby by simply removing the nut 28, the vaned member 24, the spider element 10, and the tubular element 14 can be easily and quickly removed 50 for replacement by new parts of the same or dif-

ferent design. Another advantageous feature of the construction resides in the fact that securing means for the spider element, such as bolts and screws are eliminated. It is to be understood, however, that such replacement of parts, except for the vaned member, is accomplished when the casing 5 is unthreaded from the gun barrel 6.

It will be obvious to those skilled in the art that various changes may be made in the detailed construction and arrangement of the parts described without departing from the spirit and substance of the invention, the scope of which is defined by the appended claims.

What is claimed is:

1. In a tubular casing having a portion of its inner wall surface stepped radially inwardly intermediate its ends to define a throat of reduced diameter, and the portion thereof between said throat and one end thereof of gradually increasing diameter, a supporting spider having a rod-like portion extending coaxially within said portion of gradually increasing diameter and leg portions axially abutting said stepped portion, a vaned member slidably supported on said rod-like portion and having outwardly extending vanes, said vanes having radially outermost surfaces thereof engaging said wall portion of gradually increasing diameter, and means urging said vaned member and supporting spider toward each other into tightly gripping frictional engagement respectively with the wall portions engaged thereby.

2. In a tubular casing having its inner wall surface gradually decreasing in diameter from one end for a portion of its length and then for an adjacent portion of its length stepped radially outwardly to define a Venturi passage, a spider element having a hub portion and radially outwardly extending legs, said legs axially engaging said stepped portion, a vaned member within said Venturi passage having a hub and a plurality of vanes extending outwardly therefrom, said vanes tapering substantially the same as and engaged with the tapering wall of said Venturi passage, a spindle extending coaxially through said hub portion and the hub of said vaned member, and means on said spindle element forcing said spider element and vaned member toward each other with the legs of said spindle element and the vanes

of said vaned member in clamping engagement respectively with said stepped portion and tapering wall.

3. In a recoilless gun mechanism, a tubular casing having a pressure chamber at one end and a discharge passage at the other end, the inner wall of said casing defining said chamber and passage and being stepped radially inwardly between said chamber and passage to define an entrance throat of reduced diameter for said passage, the wall of said passage flaring outwardly toward said other end, a spider within said chamber having a hub and outwardly extending legs, the outer ends of said legs axially engaging the stepped portion of said wall, a vaned member within said discharge passage and having spaced vanes peripherally engaging the flaring wall of said passage, and means coaxing with said spider and vaned member to force the legs of said spider and the vanes of said vaned member into wedging engagement respectively with said stepped portion and flaring wall.

4. In a recoilless gun mechanism, a tubular casing having a pressure chamber at one end and a discharge passage at the other end, the inner wall of said casing defining said chamber and passage and being stepped radially inwardly between said chamber and passage to define an entrance throat of reduced diameter for said passage, the wall of said passage flaring outwardly toward said other end, a spider within said chamber having a hub and outwardly extending legs, the outer ends of said legs axially engaging the stepped portion of said wall, a vaned member within said discharge passage and having a hub portion and a plurality of vanes extending outwardly therefrom, portions at least of said vanes engaging said flaring wall, a charge supporting spindle extending coaxially through said hub and said hub portion and projecting beyond said hub portion and having a shoulder portion engaging said spider at the side opposite said throat, and a nut threaded on the projecting end of said spindle in engagement with said hub portion to, in cooperation with said shoulder portion, force said vaned member and spindle axially toward each other and thereby clamp said vanes and legs against the wall portions engaged thereby.

CAROLUS L. EKSERGIAN.
